US0D1092799S

(12) **United States Design Patent** (10) Patent No.: **US D1,092,799 S**
(45) Date of Patent: ** Sep. 9, 2025

(54) **LIGHT SOURCE FOR VEHICLE INTERIOR LIGHT**

(71) Applicant: **Yazaki Corporation**, Tokyo (JP)

(72) Inventor: **Daiki Nomoto**, Shizuoka (JP)

(73) Assignee: **YAZAKI CORPORATION**, Tokyo (JP)

(**) Term: **15 Years**

(21) Appl. No.: **29/906,529**

(22) Filed: **Nov. 6, 2023**

(30) **Foreign Application Priority Data**

Jun. 8, 2023 (JP) ..... 2023-011774 D

(51) LOC (15) Cl. **26-04**

(57) **CLAIM**

The ornamental design for a light source for vehicle interior light as shown and described.

DESCRIPTION

FIG. 1 is a front, top and left-side perspective view of a light source for vehicle interior light showing my new design; FIG. 2 is a rear, top and left-side perspective view thereof; FIG. 3 is a front, bottom, and left-side perspective view thereof;

FIG. 4 is a rear, bottom and right-side perspective view thereof;

FIG. 5 is a front elevational view thereof;

FIG. 6 is rear elevational view thereof;

FIG. 7 is a left-side elevational view thereof;

FIG. 8 is a right-side elevational view thereof;

FIG. 9 is a top plan view thereof;

FIG. 10 is a bottom plan view thereof; and,

FIG. 11 is a cross-sectional view taken along line 11-11 in FIG. 9.

The broken lines shown in FIG. 8 and FIG. 11 are provided to show portions of the light source for vehicle interior light that are not being claimed, and thus form no part of the claimed design.

1 Claim, 8 Drawing Sheets
